CASING PANEL ARRANGEMENT

Louis V. Aronson, Newark, N. J., assignor to Art Metal Works, Inc., a corporation of New Jersey

Application January 14, 1933, Serial No. 651,713

9 Claims. (Cl. 41—22)

My invention relates to casings and to novel panel arrangements therefor.

My invention has particular reference to a highly satisfactory and practical arrangement for 5 securing one or more panels to a casing or the like.

Various other advantages, characteristics and features of my invention will become apparent from the following detailed description taken in 10 connection with the accompanying drawings.

My invention resides in the casings, panel arrangements, combinations and features of the character hereinafter described and claimed.

For an understanding of my invention and for 15 an illustration of some of the many forms thereof, reference is to be had to the accompanying drawings, in which:

Fig. 1 is a perspective view of a casing embodying my novel panel arrangement;

20 Fig. 2 is a transverse, vertical sectional view of the casing shown in Fig. 1;

Fig. 3 is a transverse, horizontal sectional view of the casing of Fig. 1 with one of the panels disassociated therefrom;

25 Fig. 4 is an enlarged sectional view of a panel;

Fig. 5 is a transverse, horizontal sectional view showing a modification of the invention;

Fig. 6 is an enlarged sectional view showing a modified form of panel;

30 Fig. 7 is an elevational view showing a modification of the invention;

Fig. 8 is a transverse, vertical sectional view of the casing of Fig. 7 with parts disassociated therefrom;

35 Fig. 9 is a transverse, vertical sectional view of the arrangement of Fig. 8 with the parts in assembled relation; and

Fig. 10 is a transverse, vertical sectional view illustrating another modification of the invention.

40 Referring to Figs. 1-4 inclusive, C represents any suitable casing which may be oval in horizontal cross-section or of other configuration as desired. As clearly shown in Figs. 1, 2 and 3, P and P¹ represent front and rear panels, respectively, which, in accordance with my invention, may be formed from relatively flexible material and suitably secured to said casing C.

To this end and as shown in Figs. 1, 3 and 4, the side wall of the casing C, at opposite ends thereof, carries the respective arcuate members A, A¹ which may be of metallic material and soldered or otherwise suitably secured to said casing side wall. Each of the members A and A¹ comprise end sections a which are spaced from the 45 adjacent surface of the casing side wall a distance

corresponding with the thickness of the above noted panels P and P¹.

Preferably, each of the aforesaid panels corresponds generally in configuration with that of the surface which it is to engage. Thus, as shown 5 in Fig. 3, the surfaces of the casing C engaged by the respective panels P and P¹ are generally arcuate and, therefore, it is desirable that said panels should inherently be of similar arcuate configuration. At the bottom of Fig. 3, the panel 10 P is shown by full lines in the position in which it may be held by the fingers of the workman just prior to association thereof with the casing C. While thus held and restrained, said panel P may be moved toward the adjacent side of the casing 15 C until the opposite horizontal edges thereof are disposed opposite the respective end sections a on said casing side. Then, the workman's grip on said panel P may be relaxed to permit return thereof to its normal position whereupon said 20 panel horizontal edges pass under the respective end sections a, said panel P taking the position shown by the broken lines at the bottom of Fig. 3. This constitutes a satisfactory way of assembling 25 the casing C and the panels P and P¹ although, obviously, other generally equivalent arrangements may be utilized if desired.

In the example shown in Figs. 1-4 inclusive, the panels P and P¹ are formed from pyroxylin or celluloid, it being understood, however, that other 30 suitable materials, fireproof or non-fireproof, may be utilized as desired. For example, said panels P and P¹ may be formed from cellulose-acetate material, or the like.

As shown in Fig. 4, the panel P on one face 35 thereof is engraved, grooved or channelled as indicated at b to give the effect of engine-turning on metal, these grooves causing the formation of any suitable design or representation, one example of which is shown in Fig. 1. Further, as 40 shown in Fig. 4, the grooved face of the panel P is coated with a layer c of paint or other material to give the effect of thick, smooth-covered baked enamel over the engine-turning. It will be understood that the panel P¹ is engraved and 45 coated with paint, the same as the aforesaid panel P, the designs on the two panels being different or duplicates as may be desirable.

In the form of my invention illustrated in Figs. 5 and 6, the casing C carries arcuate members A 50 and A¹ similar to those hereinbefore described. As shown at the bottom of Fig. 5, one end section a of the member A¹ occupies a lateral position with respect to said casing C. With such an arrangement, there may be utilized a panel 55

P2 which is relatively stiff and non-flexible and, as clearly appears from a consideration of Fig. 5, this panel P2 may be associated with the casing C by inserting one horizontal edge thereof beneath the end section a of the member A whereupon said panel may be brought flush against the adjacent casing surface. Thereupon, the lower end section a of the member A may be bent toward the casing C until it assumes a position similar to that occupied by the other end sections a and, in so doing, the panel P2 is positively clamped to said casing C. If desired, the panel P3 of Fig. 5 may be fixed in position in a manner similar to that just described with respect to the panel P2.

Since the panels P2 and P3 may be of relatively non-flexible material, engine-turning ornamentation represented by the grooves b may be formed on the exterior surface thereof as shown in Fig. 6.

With the forms of my invention hereinbefore described, it will be observed that the casing C comprises upper and lower flanges d and d' against one or both of which the respective upper and lower panel surfaces should engage or be closely adjacent as clearly shown in Fig. 2. With such an arrangement, it has been demonstrated that the panels remain properly associated with the casing even when the end sections a form the sole clamping means.

Referring to the form of my invention illustrated in Figs. 7, 8 and 9, it will be observed that the casing C, centrally thereof, is provided with a transverse opening formed by a tube-like member e. At one side of said casing, a panel P5 is suitably secured thereto, for example, in the manner hereinbefore described by utilization of the arcuate members A and A1. This panel P5 may have any suitable design formed thereon, it may correspond with any of the panels above described and, as appears from a consideration of Fig. 8, said panel covers the opening formed by the member e.

Secured to the casing surface opposite the panel P5 is a panel P4 which may have any suitable design formed thereon and which has an opening aligned with the opening formed by the member e; said panel P4 may be secured to the casing by arcuate members A and A1 corresponding with those hereinbefore described.

Telescopically disposed within the member e is a tube-like member f extending through said opening in the panel P4 and carrying a laterally arranged plate or disk B adapted to snugly engage and overlie a part of the panel P4. The member f is adapted to be positively retained in the member e and, to this end, it may be provided with laterally directed tips which lock behind inclined surfaces of the member e as shown in Fig. 8.

The aforesaid plate B may of such suitable configuration as desired. For example, this plate may be as shown in Fig. 7 wherein it simulates the appearance of a shield which is adapted to have carved or otherwise suitably formed thereon representations of fraternal emblems, initials, etc., etc. If desired, the plate B may serve solely or partially as the means for retaining the panel P4 in position on the casing C.

In Fig. 10, I have illustrated a modification of the invention permitting association of shield plates B and B1 with the respective front and rear casing surfaces. In accordance with this form of the invention, the panel P4, member f and plate B are associated with the casing and

its transverse member e in the manner described above in connection with Figs. 7 and 8.

However, in contradistinction to the arrangement of Figs. 7 and 8, the panel P5 of Fig. 8 is replaced, in Fig. 10, by a suitably decorated panel P7 formed with a central opening which aligns with the opening in the member f when said panel P7 is associated with the casing C. A member g extending through the opening in the panel P7 is snugly received and positively retained within the aforesaid member f. This member g carries the laterally arranged plate B1 which is adapted to overlie an exterior surface of said panel P7. It will be understood that the plates B and B1 of Figs. 9 and 10 may be duplicates of each other or not as desired and that said plates form surfaces, both at the rear and the front of the casing, for the reception of fraternal emblems, initials or the like.

As stated, the casing C may be of such character as is suitable or desirable. For example and as illustrated, it may be the fuel casing of pyrophoric lighting mechanism of any suitable character, one example of which is herein shown as comprising a reciprocatory member l which, when depressed, swings a snuffer lever 2 in a clockwise direction, Figs. 1 and 7, to expose the end of a wick extending through a wick tube 3 whereby a flame is produced all as well understood in the art.

It shall be understood that the casing C may serve otherwise than as described above. Thus, said casing C may serve as a liquid-containing receptacle for an atomizer. Or, it may be a match box or receptacle for such other articles as desired.

While the invention has been described with respect to certain particular preferred examples which give satisfactory results, it will be understood by those skilled in the art after understanding the invention, that various changes and modifications may be made without departing from the spirit and scope of the invention and it is intended therefore in the appended claims to cover all such changes and modifications.

What is claimed as new and desired to be secured by Letters Patent is:

1. A casing having its outer surface formed in part at least from a largely transparent sheet-like member having grooves on the inner surface thereof representative of engine-turning, and a coating of paint-like material covering said inner surface of said member.

2. An oval casing having metallic end sections and panels secured to opposite faces of said casing between said end sections, said panels being formed from transparent material grooved on the inner surface to form a design, and the grooves being covered with a coating of paint-like material.

3. In combination, a casing, a panel, and means extending longitudinally of said casing and coacting with the side edges of said panel for securing it to said casing, said means comprising a metallic member secured to one end of said casing, said metallic member having a lip overlying one edge of said panel.

4. In combination, a casing having a tube-like passage extending transversely therethrough, a member fixed in said passage, and a plate-like member carried by said fixed member and overlying a part of the casing side wall.

5. In combination, a casing having a tube-like passage extending transversely therethrough, a

panel overlying a surface of said casing and having an opening aligned with said passage, a member extending through said opening and fixed in said passage, and a plate-like member carried by 5 said fixed member and overlying a part of the casing side wall.

6. In combination, a casing having spaced clamping members disposed in facing relation along opposite respective sides thereof, and a 10 flexible panel overlying the surface of said casing between said members, the width of said panel being greater than the distance between the adjacent surfaces of said members.

7. In combination, a casing, a panel, and means 15 extending longitudinally of said casing and co-acting with the side edges of said panel for securing it to said casing, said panel being formed from a sheet of thin, relatively flexible material.

8. In combination, a casing, a pair of similar panels, and means for holding said panels to opposite sides of said casing in symmetrical relation with respect thereto, said panels being formed from flexible material whereby they may be bent 5 arcuately in order to associate them with said holding means.

9. The combination with a casing, of a resilient sheet-like decorative member thereon which is at least semi-transparent and has decorative configurations on its inner surface, and means fixed on the casing for receiving opposite edges of said member for securing said member to said casing and with said member flexed arcuately in a direction transverse to said edges and 10 with said edges closely engaging said means. 15

LOUIS V. ARONSON.
